UNITED STATES PATENT OFFICE.

HENRY L. PALMER, OF BROOKLYN, NEW YORK.

DESIGN FOR A CRUMB-TRAY.

SPECIFICATION forming part of Design No. 16,959, dated October 26, 1886.

Application filed September 3, 1886. Serial No. 212,643. Term of patent 14 years.

To all whom it may concern:

Be it known that I, HENRY L. PALMER, of Brooklyn, county of Kings, and State of New York, have invented and produced a new and original Design for Crumb-Trays, of which the following is a full, clear, and exact description, reference being had to the accompanying drawings, and to the letters of reference marked thereon.

10 Figure 1 is a plan or top view of my newly-designed crumb-tray, and Fig. 2 an edge view or elevation thereof looking from the edge toward the back, these views being deemed sufficient to fully illustrate my design.

15 In both figures like letters of reference, wherever they occur, indicate corresponding parts.

A is the flat bottom or main portion of the tray, of which the front edge, from *a* to *a*, is 20 straight. The rear of the flat bottom terminates in a curved line, as *b b b*, from which the curved back and sides spring. Upon the rear portion of the flat bottom is a raised or indented scroll-pattern, as *c c c*, of suitable proportions 25 to decorate the rear part, leaving the front plain and smooth. The back and sides extend upwardly and outwardly from the flat bottom, being gradually curved in both directions, and being ornamented with a series of scallops or 30 flutings, (represented at *d d*), the scallops being slightly rounded out, affording an upper margin with a series of short curves when viewed

as in Fig. 2. The handle B extends outwardly from one of the sides, the lower curved margin of the handle extending down to the front 35 edge of the side, and the upper margin and the back being joined by tangent curves, so as to present a general contour which will be pleasing to the eye. The upper surface of the handle is ornamented by suitable indented or 40 raised patterns, as *e* and *f*, which conform nearly to the general outline of the surfaces or parts on which placed.

Having now fully described my design, what I claim as new, and desire to secure by Letters 45 Patent, is—

1. The design for a crumb-tray herein described, the same consisting of the flat bottom, the curved and fluted back and side portions, and the handle extending outwardly from one 50 of the side portions and joined therewith by tangent curves, substantially as shown.

2. In a design for a crumb tray, the flat bottom portion having a scroll decoration, *c c c*, and the curved back and side portions having 55 the scallops, substantially as shown and described.

In testimony that I claim the foregoing I have hereunto set my hand in the presence of two witnesses.

HENRY L. PALMER.
